UNITED STATES PATENT OFFICE.

WILLIAM W. LEACH, OF MANSFIELD, OHIO.

BURNER.

Application filed July 30, 1920. Serial No. 400,137.

To all whom it may concern:

Be it known that I, WILLIAM W. LEACH, a citizen of the United States of America, residing at Mansfield, in the county of Rich-
5 land and State of Ohio, have invented cer-
tain new and useful Improvements in Burn-
ers, of which the following is a specification.

This invention relates to a burner for
burning powdered coal or gaseous fuel.
10 It is well known to those skilled in the
art of burning powdered coal fuel that dif-
ficulties are encountered in procuring com-
plete and proper combustion of the pow-
dered fuel as the constituent, component
15 particles thereof are so small or infini-
tesimal as to make the powdered fuel ex-
tremely light in specific gravity, therefore,
due to the fact that the powdered fuel must
be constantly fed into the furnaces through
20 the medium of an air blast or the like some
of the particles or portions thereof when
not under control and thoroughly mixed
and rotated, diffused and scattered to ad-
mit of instant combustion when subjected
25 to the flames and heat of the furnace waste
and improper combustion of the fuel nat-
urally results, and there is also an excess
of unconsumed carbon and an excess of
slag and other débris which accumulates
30 in the furnace causing, in the case of metal-
lurgical furnaces, impurities and defects in
the metal heated, as well as creating an ex-
cess amount of smoke and dirt in and sur-
rounding the furnace.

35 It is further well known that unless proper
combustion of the fuel is had that the
operation of the furnace is extremely waste-
ful in the use of fuel and that the efficiency
of the furnace is reduced below normal.

40 In the use of the conventional type of
burner now in use the powdered coal is
is forced or fed through appropriate pipe
connections or a burner by pneumatic pres-
sure such as an air blast produced by a
45 conventional type of power operated fan
which forces the fuel and air into the fur-
nace through an ordinary tubular mem-
ber, burner or pipe connections in a direct
and unbroken line from the mouth of the
50 delivery end of the burner or the like there-
by focusing an intense heat at one point
within the furnace instead of scattering and
diffusing the fuel so as to produce a uniform
heat throughout the interior of the furnace
55 which is obviated in my invention by im-
parting a revolving or rotating motion to

the air and fuel at the delivery end of the
burner or the like thereby accelerating its
proper and instant combustion by the flames
in the furnace assisted by the radiant heat
60 from the refractory walls of the furnace.

In the conventional type of burner now
in use the flow velocity of the fuel into the
furnace under air pressure is direct, contin-
uous and without means of rotating or re-
volving the fuel as it is emitted direct from
65 the delivery end of the burner into the fur-
nace instead of suspending or retarding the
travel of the fuel, and also rotating, diffus-
ing and scattering the powdered coal or
other fuel throughout the interior of the
70 furnace as is the case in the use of the pres-
ent invention which subjects the fuel to the
heat and flames of the furnace for combus-
tion purposes for a longer period of time
75 than is possible with the type of burner now
in use.

The primary object of the present inven-
tion is to design and construct a burner that
will deliver powdered coal or other like fuel
80 into the furnace in such a manner as to im-
part a whirling, rotating or revolving and
diffusing motion to the fuel thereby retard-
ing its travel in the furnace, scattering and
keeping the fuel in suspension for longer
85 periods of time at different locations within
the furnace to provide for more perfect and
efficient combustion of the fuel than can be
obtained by the use of a conventional type
90 of burner.

Another object of the present invention
is to provide a burner that is efficient in
operation and economical in the use of fuel.

A further object is to construct a burner
that will produce a whirling, revolving,
95 scattering and diffusing motion of the fuel
at the delivery end of the burner in the
same, or opposed directions or combinations
thereof.

Another object of the present invention is
to provide means of producing a concentric
series or steps of whirling motions of the
fuel and air of different diameters or radii
in the same, or opposed directions or com-
binations thereof.

A further object is to provide a means of
swinging the burner and doors of the fur-
nace to either closed or open positions in
either direction and afford facilities for per-
mitting the slag, dirt or débris to drip
100 from the furnace without opening the main
doors of the furnace or affecting the burner.

These and other objects are attained by the mechanism illustrated in the accompanying drawings in which:

Fig. 1 is a front elevation of the invention showing it applied to a furnace.

Fig. 2 is a side elevation of the structure shown in Fig. 1 shown partly in section.

Fig. 3 is a sectional view of a flange clamping mechanism used to connect or disconnect the pipe connections to or from the burner.

Fig. 4 is an end view of one of the flange members of the clamping mechanism.

Fig. 5 is a horizontal sectional view of the invention showing the series of spirals and their associated relation to each other and the concentric tubular members of the burner.

Fig. 6 is a horizontal sectional view similar to Fig. 5 with the spirals removed to clearly show the arrangement of the concentric tubular members.

Fig. 7 is a cross section on line 7—7 of Fig. 6 with the spirals in place showing the direction of the travel of the fuel and air in the preferred form.

Fig. 8 is a longitudinal sectional view of the furnace showing the burner applied thereto in operative position in full lines and in inoperative position in dotted lines.

Fig. 9 is an end view of the burner on an enlarged scale showing the arrangement of the spirals within the concentric tubular members.

In the drawing the invention is shown applied to the front plate of a conventional type of sheet or bar metal furnace which is equipped to burn powdered fuel coal as the burner is efficient, economical and practical in attaining the objects herein set forth in burning powdered coal.

It is equally, however, as efficient and economical in burning gaseous fuel or the like and the same results are obtained.

Reference numeral 1 represents the front plate of a conventional type of sheet or bar furnace to which the invention is preferably applied showing it in association with means for conducting powdered fuel and the primary fuel propelling air, and the means of conducting secondary air to the burner. The desired opening is provided in the front plate and ears 2—2—3—3 preferably formed thereon. A main door 5 is provided with ears 6—6 and 7—7 and is supported on the ears 2 and 3 and adapted to be swung in either direction that is, either toward the right or left side of the furnace upon the pintle rods 8 and 9 thereby providing a hinged door that can be opened or closed from the right or left side.

In constructing the main door and hinge same to the front plate so that it can be manipulated from either side utility and

convenience are obtained as other equipment of the furnace may be located on one side that can be avoided by swinging the door to and from the opposite side of the furnace. An auxiliary door 10 used to permit access to the furnace fire pot without disturbing the main door is also mounted upon the furnace front which auxiliary door is constructed and mounted thereon to operate in the same manner as the door 5 hereinbefore described. A door 11 is provided and hinged to the door 10 to open in a vertical direction which permits the slag, dirt, ash or other débris to drip, fall, flow or to be drawn out of the fire box of the furnace without disturbing either of the doors 5 or 10. The door 11 is normally held in yielding closed position by the weight of the knob 12. A suitable opening 13 is provided in the door 5 and a member 14 is secured therein with its flange portion 15 surrounding and overlapping the edge of the opening 13 as shown in Fig. 8. The member 14 is preferably formed to provide inclined or flaring mouth portions 16 and 17 in opposed relation to each other. Ears 18 are preferably made integral with the member 14 and spaced apart from each other to receive and support the outwardly extending arms 19 and 20 which are arranged in opposed relation on the sides of the burner 21.

The burner is preferably supported on the ears 18 and held in place thereon by pins 22 and 23 permitting it to be swung toward the right or left side of the furnace. Powdered coal combined with primary air under pressure is conducted to the burner from any source of supply by the pipe 24. The pipe 24 is connected to the burner by the flange connections 25 and 26 and the nipple 26. The complementary parts of the flange 25 are held in close and frictional contact with each other by bolts 27 and 28 and the lever nuts 29 and 30. The complementary parts of the connecting flanges are provided with slots 31 and 32 to permit of the parts to be disconnected from each other or connected to each other without withdrawing the bolts. The separation of the parts or their close connection is accomplished by loosening or tightening the lever nuts 29 and 30. As will be observed the primary air combined with powdered coal or other like fuel is delivered into the end of the burner 21. It is customary to supply the burner for burning powdered coal or the like with additional or secondary air under pressure to assist in the delivery of the powdered coal in the furnace when the pressure of the primary air is insufficient.

To supply the additional or secondary air under pressure a conducting air pipe 33 is provided and preferably connected to the burner to deliver the air into the burner at

the top adjacent to its front end. The connections 34, 35 and 35' of the secondary air pipe and burner are similar to the connections 25 and 26 and 26' of the primary pipe connections hereinbefore described. In the construction of the burner a tubular member 36 is provided which comprises the outer casing. The outer casing 36 is provided with an enlarged end portion 37 to receive 10 and engage the flange 26 of the nipple 26' which is connected to the pipe 24 as described. A flange engaging portion 38 is provided on the top of the casing to connect with the flange 35 and it is arranged in a 15 right angular relation to the enlarged portion 37 of the burner casing thereby providing right angularly related means of conducting air to the burner in conjunction with the means of supplying air at the front 20 end of the burner. The flange 26 is provided with a hub portion 39 which is screw threaded at both ends to engage the nipple 26' and one end of a tubular member or pipe 40 which pipe is smaller in diameter than 25 the member 36 and it is arranged within the tubular member in concentric relation thereto. Spirally formed deflectors or vanes 41 are secured within the pipe 40. The deflectors wind spirally around the interior of the 30 pipe 40 in spaced relation to each other thereby forming spiral paths through which the powdered coal or other fuel travels and is driven, forced and delivered into the furnace by air under pressure.

35 The combined air and powdered coal is preferably forced to travel around the interior of the pipe 40 in a clockwise direction as shown in Fig. 7. A second series of spiral air deflectors or vanes 42 are secured to the 40 periphery of the pipe 40 commencing beyond the opening of the flange 38. The deflectors 42 provide a series of spiral paths for the air running in counter-clockwise direction to that of the deflectors 41. The diameter of the spiral paths formed by the deflectors 42 are likewise increased with respect to the deflectors 41. An intermediate tubular member 43 is fitted to the periphery of the deflectors 42 leaving a space 44 between its periphery and the interior of the outer tubular member 36.

45 A third series of spiral deflectors or vanes 45 are secured to the periphery of the intermediate member 43 spirally preferably winding around said member in the same direction as the deflectors 41 within the tube 40. It will be observed that the tubular members 36, 43 and 40 are arranged in relatively co-axial and concentric relation with respect to 50 each other, but, that their free ends successively overlap each other for the purpose of emitting the secondary air and combined primary air and fuel at different points within the burner so as to aid in scattering and diffusing the air and fuel just prior to

delivering into the furnace. The ends of the spiral deflectors as shown by the deflectors 42 in Fig. 5, may project beyond the tubular members which serves to break and diffuse the air currents to some extent. 70

The operation of the burner in brief is as follows: Primary air under pressure forces the powdered fuel or the like through the pipe 24 and its connection to the burner and thence through the spiral paths formed by 75 the member 40 and the spiral deflectors 41 into the furnace at its free end. The fuel and air on account of its spiral travel delivers the combined air and fuel into the furnace in a rotating, revolving or whirling motion thereby scattering and diffusing the fuel and air to all parts of the furnace and suspending same for a longer period of time thereby subjecting the fuel to the flame and radiant heat of the furnace longer and at 80 more different points within the furnace than is possible with the use of an ordinary burner. The deflectors 42 and 45 function in the same manner as described with reference to the deflectors 41 except that the deflectors 90 42 wind around and form spiral paths in an opposite direction to that of the spiral deflectors 41 and 45.

85 It will be apparent from the construction and operation of the burner that a series of spiral paths is provided for the air and fuel of different diameters, that the paths deliver the air and fuel into the furnaces in stepped relation so that if a charge of fuel delivered with the primary air is not of 95 proper proportion to the air to insure proper combustion in the first instance it is acted upon by each of the other rotating and revolving air currents in sequence.

100 It will further be noted that the travel of the air and fuel through the different spiral paths delivers such air and fuel at different points within the burner thereby further assisting in agitating and suspending the fuel. 105

110 The invention herein described can be used for gaseous fuel if desired and one or more series of spiral paths can be formed for the purpose herein described without departing from the spirit of the invention. 115

115 It is not intended to confine the invention to the structure shown and described herein or to its application for burning powdered fuel.

120 I claim:

1. A burner including a fuel tube, means for imparting a whirling movement to the fuel within the tube, a series of air pipes co-axially arranged with the tube and with each other, and spiral deflectors arranged in the spaces between the tube and adjacent pipe and between the pipes. 125

2. A burner including a fuel tube, means within the tube for imparting a whirling movement to the fuel, a pipe co-axially ar- 130

ranged with the tube, a series of spiral deflectors between the tube and pipe, a second pipe concentric with the first pipe, and a series of spiral deflectors between said pipes.

5 3. A burner including a tube for the passage of fuel, fuel whirling means arranged in said tube, an air pipe co-axially arranged with and extending beyond said tube, air whirling means arranged between said tube 10 and pipe, a second air pipe concentric with the first air pipe and extending beyond the same, and air whirling means arranged between said pipes.

15 4. In a burner, a tubular member to initially receive fuel and air and having provided therein a series of spiral deflectors, a plurality of tubular members of larger diameter arranged in spaced, stepped and co-axial relation thereto, spiral deflectors 20 arranged in the spaces between said members and means to provide air for said tubular members of larger diameter and means to provide air for the first mentioned tubular member under pressure for the delivery 25 of fuel.

5 5. In a burner, a tubular member having spiral deflectors secured to the interior thereof, means of feeding combined air and fuel thereto, a second tubular member provided with a series of spiral deflectors 30 mounted in co-axial and spaced relation to the first mentioned tubular member, means to force air under pressure thereto, and a third tubular member co-axial with 35 the other tubular members and provided with a spiral deflector associated with the first mentioned tubular member, said spiral deflectors and tubular members being adapted to impart whirling and revolving motions to the air and fuel in opposed relations 40 to each other.

45 6. In a burner, three tubular members arranged in co-axial relation to each other, spiral deflectors associated therewith, means to supply air and fuel under pressure to one of the tubular members, means to supply air under pressure without fuel to two of the tubular members, the combination of the tubular members and deflectors being 50 arranged to deliver fuel in a whirling motion and whirling streams of air in the same and opposed relation to the whirling fuel for the purpose of suspending and agitating the fuel for combustion purposes, as 55 described and set forth.

7. A burner having concentric members

defining three separate paths lengthwise of said burner, means for delivering fuel with a whirling motion through one path, and means for delivering air with relatively- 60 opposite whirling motions through the remaining paths.

8. A burner having concentric members defining three separate paths lengthwise of said burner, means for delivering fuel with 65 a whirling motion through one path, and means for delivering air with relatively- opposite whirling motions through the remaining paths, such separate paths merging 70 into a single outlet from the burner.

9. A burner having an interior fuel delivery tube, deflectors therein, a second tube co-axial with the first tube and spaced therefrom, deflectors arranged in the space between said tubes, a third tube co-axial with 75 the second tube and spaced therefrom exteriorly, and deflectors in the space between said second and third tubes.

10. A burner made up of a plurality of tubular bodies arranged in concentric spaced 80 relation with their delivery ends relatively offset to thereby define three spaces lengthwise of the burner, and deflectors arranged in each of said spaces, the deflectors of adjacent spaces being oppositely arranged. 85

11. A burner made up of a plurality of tubes arranged in concentric spaced relation to thereby define three spaces lengthwise of the burner, deflectors arranged in each of said spaces, the deflectors of adjacent spaces being oppositely arranged, 90 means for delivering fuel to one of said spaces, and means for delivering air to the remaining spaces.

12. A burner comprising an outer tube, 95 an inner tube concentric therewith, and an intermediate tube between and spaced from said outer tube and inner tube, deflectors arranged in said inner tube, and deflectors arranged in each of the spaces between the inner tube and intermediate tube and between the latter and outer tube, means for delivering fuel lengthwise the inner tube, and means for delivering air lengthwise the outer tube and intermediate tube, the inner tube terminating short of the delivery end of the intermediate tube, and the intermediate tube terminating short of the outer tube. 100 105

In testimony whereof I affix my signature.

WILLIAM W. LEACH.
